UNITED STATES PATENT OFFICE.

LARS PEDERSON, OF MANITOWOC, WISCONSIN.

ROTARY STEAM-ENGINE.

SPECIFICATION forming part of Letters Patent No. 650,339, dated May 22, 1900.

Application filed September 29, 1899. Serial No. 732,051. (No model.)

To all whom it may concern:

Be it known that I, LARS PEDERSON, a citizen of the United States, residing at Manitowoc, in the county of Manitowoc and State 5 of Wisconsin, have invented new and useful Improvements in Rotary Steam-Engines, of which the following is a specification.

My invention relates to rotary steam-engines; and its object is to provide an improved 10 construction of the same whereby back pressure of the steam on the piston is effectually prevented.

It is also an object to improve the construction generally, so that it will possess superior 15 advantages with respect to efficiency in operation.

The invention consists in the novel construction and combination of parts hereinafter fully described and claimed.

20 In the accompanying drawings, Figure 1 is an elevation of a rotary engine constructed in accordance with my invention, the removable section or part to which the rotatable piston-wheel is journaled being removed. Fig. 2 is a similar view of the removable section and piston-wheel looking from the inner side. Fig. 3 is a horizontal section on the line xx , Fig. 1, showing the removable section secured to the stationary section or casting.

30 In the said drawings the reference-numeral 1 designates the stationary portion or section of the engine, consisting of a rectangular casting formed with a circular or cylindrical recess 2, in which the piston-wheel, hereinafter described, rotates. Near the upper end and at opposite sides said casting is provided with valve-chambers 3, in which are seated semi-cylindrical or half-round oscillatory valves 4, which are pivotally connected therewith and 35 with the removable section by journals 5. These journals extend through said casting and are connected with each other by a rod 5^a, so as to move in unison. These valve-chambers communicate with the recess in the casting 40 by passages 6 and are also provided with inlet-passages 7, communicating with a steam-chest 8. Each valve-chamber is provided with exhaust-passages 9 and exhaust-pipes 10. Located and journaled centrally thereto is a 45 rotatable piston 12, cut away at the inner end, as seen at 13, the outer or free ends being of a width equal to the depth of the said recess.

The shaft of this piston extends through the casing and is provided with an eccentric 12^a, which is connected with one of the valves 4, 55 as shown in dotted lines, Fig. 1. As the said piston rotates, as hereinafter described, the eccentric will operate the valve connected therewith, which, being connected with the other valve, will cause said valves to be alternately operated to open and close the steam-passages, as will be understood by those acquainted with the art to which the invention pertains.

The numeral 14 designates the rotatable 65 piston-wheel, located in said recess 2, but eccentric thereto.

The numeral 15 designates the driving-shaft to which said wheel is secured, journaled to the removable section 16 and provided with a driving wheel or pulley 17. The opposite faces of this wheel, near the rim or periphery, are formed with circular grooves 18 to receive a packing 19 of any suitable material. This section is bolted to the casting 1 and in the present instance is shown as being composed of three parts or pieces, although it may be made of a single piece, if desired. Said wheel in one face is formed with a circular recess 20 and is also formed 70 with a triangular opening 21, the sides of which are beveled, as seen at 23. The enlarged end of the piston is located in this opening and is adapted to project through an intersecting passage 24 in the rim of the 75 wheel, which passage is provided with guide-rollers 24^a.

It will be seen that at one point the piston-wheel will impinge against the casting, and owing to the eccentricity of the said wheel to 90 the recess in the casting from said point where the wheel impinges there is a gradually-increasing space, which space is greatest at a point centrally between the valve-chambers. For the purpose of preventing escape 95 of steam between the wheel and casting, which would tend to react or cause a back pressure upon the piston, the casting is cut away at 25, forming a curved chamber in which is located a curved spring-metal plate 26, secured 100 to said casting by a bolt 27. It will be seen that the ends of this plate are so bent that they press against the periphery of the piston-wheel under spring tension, and thus

make a tight joint, but without interfering with the working of the wheel.

The operation is as follows: One of the valves is turned so that communication between the inlet-passages of one valve-chamber is brought into communication with the steam-space between the piston-wheel and the casting, while the other valve is turned so as to bring the said space into communication with the exhaust-passage. Steam being now admitted to the valve-chamber first mentioned will act upon the piston and rotate the wheel and driving-shaft. The steam escapes through the exhaust-passage of the other valve-chamber. If desired, two or more pistons may be employed, which will be preferable, so that the rotation of the wheel will be uniform.

It will be obvious that several engines may be connected together so as to secure uniformity of operation.

Having thus fully described my invention, what I claim is—

A rotary engine consisting of a casing hav-

ing a cylindrical recess therein and a steam-chest above it, steam-ports communicating with said cylindrical recess at each side above the center thereof, circular recesses above said ports, semicircular valves seated in said recesses, inlet-ports extending from the steam-chest to the inner sides of the recesses, exhaust-ports extending from the outer sides of said recesses up through the top of the casing, a rotary piston-wheel journaled eccentrically in the cylindrical recess in the casing, said wheel having triangular openings in the periphery thereof and a rotatable piston moving in said opening, the face of said piston-wheel having an annular groove therein, and a packing in said groove, substantially as described.

In testimony whereof I have hereunto set my hand in presence of two subscribing witnesses.

LARS PEDERSON.
